(57) **CLAIM**

The ornamental design for a laptop protective case, as shown and described.

DESCRIPTION

FIG. 1 is a front perspective view of a laptop protective case, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the front in its closed state; and,

FIG. 10 is a perspective view of the back in its closed state. The broken lines in the drawings illustrate the portions of the laptop protective case, which form no part of the claimed design.

1 Claim, 10 Drawing Sheets
